Edwin Thomas, Inventor.

United States Patent Office.

EDWIN THOMAS, OF PHILADELPHIA, PENNSYLVANIA.

Letters Patent No. 78,027, dated May 19, 1868.

IMPROVEMENT IN NECK-TIES.

The Schedule referred to in these Letters Patent and making part of the same.

TO ALL WHOM IT MAY CONCERN:

Be it known that I, EDWIN THOMAS, of the city of Philadelphia, county of Philadelphia, and State of Pennsylvania, have invented a new and useful "Improvement in Neck-Ties;" and I do hereby declare that the following is a full, clear, and exact description of the construction and operation of the same, reference being had to the accompanying drawings, making a part of this specification, in which—

Figure 1 is a view of my tie complete.

Figure 2 is a detached view of the catch.

Figure 3 is a view of my tie fastened in a bow.

The nature of my invention consists in forming a neck-tie of various-colored pieces, of any material, held together by means of a catch, as hereinafter described, so as to form a tie of ordinary length, that will be reversible or changeable to any colored bow and ends desired.

To enable others skilled in the art to make and use my invention, I will now proceed to describe its construction and operation.

A, B, C, D, and E, fig. 1, represent a series of pieces of silk or other material, of the required length, the ends of which are fringed similar to the ends of pieces A and F. I now insert the ends in the receptacles *b* and *b'* of the catch F, fig. 2. Said catch consists of a piece of fabric, of the same texture as the pieces A, B, and C, with the inner side provided with a toothed plate, set diagonally across, and held in place by means of stitches.

The tie, fig. 1, when fastened to the neck, will form a brown bow and ends. Now, should the wearer desire to have the bow and ends red, blue, or any other color, the pieces A, B, and C are detached, and the desired color set on the ends.

It will be obvious that my neck-tie will wear evenly in all its parts, and enable the wearer to have a different bow and ends, of any desired color, in one neck-tie.

If desired, a small buckle (covered) can be substituted for the catch, so as to answer the same purpose.

Having thus described my invention, its construction and operation, what I claim, and desire to secure by Letters Patent, is—

As a new article of manufacture, a neck-tie, composed of sections of material of different colors or quality, said sections being detached from each other, substantially in the manner specified, and for the purpose set forth.

EDWIN THOMAS.
